Primary Examiner — Holly Bayham*Assistant Examiner* — Rashida C Walshon(74) *Attorney, Agent, or Firm* — Crose Law LLC;
Bradley D. Crose(57) **CLAIM**

The ornamental design for a lace point, as shown and described.

DESCRIPTION

FIG. 1 is a front perspective view of a lace point, illustrating the new, original, and ornamental design;

FIG. 2 is a front planar view of the lace point;

FIG. 3 is a back planar view of the lace point;

FIG. 4 is a top planar view of the lace point;

FIG. 5 is a bottom planar view of the lace point;

FIG. 6 is a left side planar view of the lace point;

FIG. 7 is a right side planar view of the lace point; and,

FIG. 8 is a view of a pair of lace points shown in use

securing a lace within a shoe in an untied position.

The broken lines shown in the drawings are included for the purpose of illustrating environmental structure and form no part of the claimed design.

1 Claim, 3 Drawing Sheets(56)
